OPHTHALMIC MOUNTING OR THE LIKE

Raymond L. Wells, Attleboro, Mass., assignor to American Optical Company, Southbridge,
Mass., a voluntary association of Massachusetts

Application October 20, 1948, Serial No. 149,201

Term of patent 14 years

(Cl. D57--1)

To all whom it may concern:

Be it known that I, Raymond L. Wells, citizen of the United States of America, residing at Attleboro, in the county of Bristol and State of Massachusetts, have invented a new, original, and ornamental Design for an Ophthalmic Mounting or the like, of which the following is a specification, reference being made to the accompanying drawings, forming a part thereof.

Fig. 1 is a front elevational view of an ophthalmic mounting, showing my new design.

Fig. 2 is a top plan view of Fig. 1, the temples being shown fragmentarily for convenience of illustration.

Fig. 3 is a side elevational view thereof.

The essential features of my design for an ophthalmic mounting or the like, reside in the parts shown in full lines in the drawings, and more specifically the top arms of the mounting shown in full lines which taper gradually toward the point of connection with the temples, all as illustrated on the drawing.

I claim:

The ornamental design for an ophthalmic mounting or the like, substantially as shown and described.

RAYMOND L. WELLS.
